UNITED STATES PATENT OFFICE.

PHILIP CUTHBERT PHIPPEN BOOTY, OF WINDSOR, VICTORIA, AUSTRALIA.

CARBURETER.

1,201,013.

Specification of Letters Patent. Patented Oct. 10, 1916.

Application filed April 20, 1915. Serial No. 22,668.

To all whom it may concern:

Be it known that I, PHILIP CUTHBERT PHIPPEN BOOTY, subject of the King of Great Britain, residing at No. 15 Punt road, 5 Windsor, in the State of Victoria, Australia, have invented certain new and useful Improvements in Carbureters, of which the following is a specification.

This invention relates to a carbureter for 10 charging atmospheric air with the vapor of petrol or other volatile hydrocarbons.

The object of the invention is to provide an improved carbureter whereby the mixture is automatically supplied according to 15 the take off of the mixture, and whereby the air and petrol or other volatile hydrocarbons are mixed in predetermined and approved proportions and irrespective of the amount of the take off of the mixture.

20 The construction and use of the device will be explained with the aid of the attached drawings in which—

Figure 1 shows a sectional elevation and Fig. 2 a plan thereof. Fig. 3 a plan of the 25 gas bell. Fig. 4 a plan of gas valve cone. Fig. 5 a plan of gas valve cone support. Fig. 6 a sectional plan of petrol valve ring. Fig. 7 a plan of petrol valve chamber. Fig. 8 an enlarged detail section of the upper 30 portion of the valve chamber. Fig. 9 a partial plan of a section through the petrol valve stem.

In the said drawing 1 designates the carbureter casing having the concentric well 2 35 for holding the glycerin, water or other sealing agent and into which dips the inverted and floating bell 3 having the central support 4 carrying the valve tube 5 and petrol valve 6. The valve tube 5 has an internal 40 flange at its lower end 5^a to fit the larger end of the valve cone 7.

The petrol valve 6 is supported by the floating bell 3 and is kept in a central position by passing through the valve cone 7 45 and the petrol valve ring 8. The petrol valve 6 consists of a vertical rod of metal provided with a tapering groove or slot 6^a or other means for gradually varying the sectional area of such portion of its length 50 sliding through the petrol valve ring 8. The lower portion terminates in a cone to suit the petrol valve seat 9.

The valve cone 7 is supported in a central position by the stationary valve cone sup- 55 port 10, into the lower portion 10^a of which the petrol flows as hereinafter described.

To such portion 10^a is fitted a pipe 11 terminating in a drip point 12 from whence the petrol falls into the carbureting chamber 26. The gas valve cone support 10 is provided with the slots or openings 10^b in order that the pressure within the casing 13 may be freely maintained around the top of the petrol valve ring 8.

The casing 13 carries a bracket 14 having a split or spring eye or other adjustable clamping device 15 which adjustably supports the petrol float chamber 17. By means of this construction the vertical position of the petrol float chamber 17 is regulated so as to govern the pressure at which the petrol is supplied by means of the feed pipe 18 and the connection 19 to the petrol chamber 19^a. The said petrol float chamber 17 is supplied from a petrol tank as usual 75 through the filter 20^a and the pipe 20.

The casing 13 is provided with two pipes 21, 22 whose function is respectively to maintain an equilibrium of pressure within the casing 13 the float chamber 17 and the 80 petrol tank (not shown in the drawings). The casing is also provided with the sight feed glass 25 by means of which the flow of petrol from the drip point 12 into the carbureting chamber may readily be observed. 85

The action of the appliance is automatic and is as follows:—In the drawing the bell 3 is shown in its lowermost or closed down position with the flanged end of the tube 5 fitting the large end of the cone 7 and 90 the coned end of the petrol valve 6 resting on its seat 9 and the tapering grooved portion 6^a below the petrol valve ring 8 which positions are maintained as long as there is no take off of carbureted air through the 95 pipe 23.

As soon as carbureted air is taken off, the pressure in the carbureted air chamber 24 above the bell 3 is reduced, the pressure from below then operates and causes the 100 bell to rise and carry with it the petrol valve 6 and the valve tube 5 until the latter assumes such a position relative to the fixed valve cone 7 that the requisite area is provided by the annular space formed between 105 the flanged end 5^a of the tube 5 and the cone 7 to allow carbureted air to pass through and into the upper chamber 24 to reestablish the pressure and supply the amount of carbureted air called for 110 through the pipe 23. The rising of the bell carries with it the petrol valve 6 which

leaving its seat 9 allows the petrol to flow in an upward direction into the upper portion of same and thence between the slot 6^a of the valve 6 and the ring 8 at a rate 5 proportionate to the height to which it is lifted. Through the lower portion 10^a of the cone support 10 the petrol passes to the pipe 11 and is fed through the drip point 12 into the mixing chamber. In the 10 latter chamber the dripping petrol meets the incoming air whereby carbureted air of a fixed quality is generated predetermined by the proportionate areas of the 15 annular space formed by the flange 5^a on the tube 5 and the cone 7 and the area of the groove or slot 6^a in the petrol valve 6 when opposite the ring 8 through which it passes.

It will be apparent that the greater the 20 consumption of carbureted air the higher the bell will rise and consequently the wider the petrol valve will be opened and the greater the feed of petrol to the carbureting chamber all in proportion to the 25 amount of carbureted air passing to the delivery pipe.

I claim:—

1. In a carbureter provided with a carbureted air chamber and a floating bell, a 30 valve device consisting of a tapered gas valve and a petrol valve formed with a tapered groove each of said valves being automatically controlled by said bell.
2. In a carbureter provided with a carbureted air chamber and a floating bell, a 35 petrol control valve formed with a tapered groove and connected with said bell and a ring in which said valve is slidably mounted.
3. In a carbureter provided with a car- 40

bureted air chamber and a floating bell, a petrol control valve located in a chamber and connected with said bell, a conical termination to said valve and a tapered groove formed therein, a seating on the lower entrance portion of said chamber to receive said conical termination, a ring in which said valve is slidably mounted, and an outlet pipe above said ring provided with a drip point. 45

4. In a carbureter provided with a carbureted air chamber and a floating bell, a carbureting chamber, a mixture valve consisting of a depending tube on said bell formed with an inturned flange at its lower 50 end and a stationary cone over which said end is fitted, and a valve for admitting petrol to said carbureting chamber.

5. In a carbureter provided with a carbureted air chamber and a floating bell, a 60 petrol control valve consisting of a vertical rod attached to said bell and formed at the lower portion with a coned end and with a tapered groove, a carbureting chamber, a ring through which said lower portion 65 passes to supply petrol thereto and a mixture supply valve consisting of a depending tube on said bell formed with an inturned flange at its lower end, and a stationary cone over which said lower end fits and attached to a support provided with openings and with a petrol outlet above said ring. 70

In testimony whereof I have hereunto set my hand in presence of two subscribing witnesses.

PHILIP CUTHBERT PHIPPEN BOOTY.
